(57) CLAIM

We claim the ornamental design for a teeth-whitening equipment, as shown and described.

DESCRIPTION

FIG. 1 is a top, front and right perspective view of a teeth-whitening equipment showing our new design;

FIG. 2 is a bottom, rear and left perspective view thereof;

FIG. 3 is a rear view thereof;

FIG. 4 is a front view thereof;

FIG. 5 is a left side view thereof;

FIG. 6 is a right side view thereof;

FIG. 7 is a bottom view thereof; and,

FIG. 8 is a top view thereof.

The broken lines depict portions of the teeth-whitening equipment in which the design is embodied that form no part of the claimed design.
